UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 23, 1924. Serial No. 687,960.

My invention relates to railway traffic controlling apparatus, and particularly to apparatus of the type comprising train carried governing means received from the trackway. More particularly my invention relates to the trackway portion of such apparatus.

I will describe one form of trackway apparatus embodying my invention, and will then point out the novel features thereof in claims.

In the accompanying drawings, Figs. 1 and 2, when placed end to end with Fig. 2 on the right, constitute a diagrammatic view showing one form of railway traffic controlling apparatus embodying my invention.

Referring to the drawings, the reference characters 1 and 1^a designate the track rails of a stretch of a railroad over which traffic normally moves in both directions. This stretch is provided at its left hand and right hand ends with passing sidings X' and X^a, respectively. It is understood that a number of portions of track such as shown in the drawing could be placed end to end to form a complete system consisting of stretches of single track separated by passing sidings. The track shown in the drawing is divided by means of insulated joints 2 into a plurality of track sections A—B, B—C, C—D, D—E, E—F, F—G, G—H and H—J, etc.

Traffic moving from right to left, that is, westbound traffic over the stretch of track shown in the drawing, is governed by trackway signals W⁴, W⁸, W¹⁴ and W¹⁸ located at points H, F, C and A, respectively. In a similar manner eastbound traffic, that is, traffic moving from left to right through the stretch of track shown in the drawing, is governed by signals W', W⁵, W⁹, and W¹⁵ located at points A, C, E and H, respectively. The signals W may be of any suitable type and as here shown are three-position semaphore signals, each comprising a semaphore blade capable of assuming three distinctive positions at 0, 45 and 90 angular degrees with respect to the ground in which positions the signal displays a stop indication or a caution indication or

a proceed indication, respectively. The signals are controlled in accordance with standard practice in absolute permissive block signaling, so that when a westbound train passes signal W⁴ the opposing signals W', W⁵, W⁹ and W¹⁵ assume the stop indication, and when an eastbound train passes signal W', signals W⁴, W⁸, W¹⁴ and W¹⁸ assume the stop indication; whereas the signals governing traffic in the direction in which a train is moving operate in accordance with standard double track signaling. The means by which the signals are controlled in this manner forms no part of my present invention, and is therefore omitted from the drawing for the sake of simplicity. Associated with each signal W is a circuit controller designated by the reference character K with an exponent corresponding to the location and arranged to occupy one position when the associated signal indicates proceed or caution and to occupy a different position when the associated signal indicates stop. Each of the signals except W¹⁴ and W¹⁸ is further provided with a circuit controller designated by the reference character P with an exponent corresponding to the location. The purpose and function of each device K and P will appear as the explanation proceeds.

Each track section is provided with a direct current track circuit comprising a battery 10 constantly connected with the rails adjacent one end of such section and a direct current track relay here designated by the reference character R with a suitable exponent and constantly connected with the rails adjacent the other end of the section. For example, sections A—B, C—D, E—F, F—G and H—J each comprise a battery 10 located at its right hand end and a relay R located at its left hand end. The remaining sections B—C, D—E and G—H and the partial sections immediately to the left of point A and immediately to the right of point J are provided with batteries 10 adjacent their left hand ends and relays R adjacent their right hand ends.

Associated with each signal W¹⁵, W⁹, W⁸ and W¹⁴ is a stick relay designated by the reference character S with an exponent

corresponding to the location. Each such stick relay is controlled by means not shown in the drawing in such manner that when a train moving in the direction in which the 5 signal governs, passes the associated signal, the relay is energized, provided the signal is displaying a proceed or a caution indication, and the stick relay thereafter remains in its energized condition until the 10 entire train passes the next signal in advance.

Each track section is also provided with two sources of alternating track circuit current, here shown as track transformers, one 15 located at each end of each section and designated by the reference characters T with exponents corresponding to the locations. The secondary 11 of each track transformer T which is located adjacent the track relay 20 R is connected in parallel with such relay, whereas the secondary 11 of each track transformer T which is located at the battery end of a section is interposed between such battery and one rail 1^a of the corresponding section. The primary 12 of each track transformer T is at times supplied, 25 as will be hereinafter explained, with alternating current from certain line transformers located at intervals with the trackway and each designated by the reference character O with a suitable exponent. The primary of each line transformer O is 30 constantly supplied with alternating current from one phase of a quadrature two-phase 35 alternator M over line wires 3 and 3^b.

The energization of each track transformer, that is, the supply of alternating current to the primary of such transformer, is controlled in part by a signal located in 40 advance of the transformer. For example, when signal W⁵ indicates proceed or caution, and stick relay S⁵ is de-energized, and relay R¹⁴ is energized, a circuit is closed over which current flows from secondary 13 of 45 transformer O^c, over wire 14, contact 15-16 of circuit controller K⁵, wire 17, back contact 18 of stick relay S⁵, wire 19, impedance 6, primary 12 of transformer T¹⁴, wires 20 and 21, contact 23-24 of circuit controller K⁵, wire 50 25, front contact 26 of relay R¹⁴, and wire 27 back to secondary 13 of transformer O^c. It will be plain that when this circuit is closed alternating track circuit current of 55 one relative polarity which I will term "normal relative polarity" is supplied to section A-B by transformer T¹⁴. Another circuit is provided which passes from secondary 13 of transformer O^c, through wire 14, contact 15-23 of circuit controller K⁵, wires 21 60 and 20, primary 12 of transformer T¹⁴, impedance 6, wire 19, front contact 18 of relay S⁵, wire 28, contact 29-24 of circuit controller K⁵, wire 25, front contact 26 of relay R¹⁴, and wire 27 back to secondary 13 of 65 transformer O^c. This circuit is closed only

when signal W⁵ is at stop and relays R¹⁴ and S⁵ are both energized, under which conditions alternating track circuit current of the other relative polarity, which I will term "reverse" relative polarity, is supplied to section A-B by transformer T¹⁴. When signal W⁵ indicates caution or proceed and relay R¹⁴ is de-energized, a circuit is closed over which current flows from secondary 13 of transformer O^c, through wire 14, contact 15-16 of circuit controller K⁵, wires 17 70 and 18, primary 12 of transformer T¹⁴, wire 30, back contact 26 of relay R¹⁴, and wire 27 back to secondary 13 of transformer O^c. When this circuit is closed alternating track circuit current of normal relative polarity is supplied to section B-C by transformer T¹⁴.

The control of transformers T¹⁰ and T¹² by signal W⁹ and the control of transformers T¹¹ and T¹³ of signal W⁸ will be readily understood from the foregoing.

Referring now to signal W¹⁸, the circuit controller K¹⁸ associated with this signal operates as a pole changer to supply current of normal or reverse relative polarity to transformer T⁸. To accomplish this result contact members 15 and 24 of circuit controller K¹⁸ are connected by means of wires 31 and 35 with the terminals of secondary 13 of transformer O⁸. The circuit for 95 transformer T⁸ passes from contact members 23 of circuit controller K¹⁸, wire 22, front contact 32 of relay R⁸, wire 33, impedance 6, primary 12 of transformer T⁸, wires 34, 20 and 21, back to contact member 100 16 or contact member 29 of circuit controller K¹⁸. It follows that when relay R⁸ is energized section B-C is supplied by transformer T⁸ with alternating track circuit current of normal relative polarity 105 when signal W¹⁸ is at proceed or caution, and with alternating track circuit current of reverse relative polarity when signal W¹⁸ is at stop. When relay R⁸ is deenergized the supply of current to transformer T⁸ is interrupted at front contact 32 thereon and a circuit is closed, providing signal W¹⁸ indicates caution or proceed, over which current flows from contact member 23 of circuit controller K¹⁸, through wire 22, back contact 110 32 of relay R⁸, wire 36, primary 12 of transformer T⁸, wire 37, circuit controller K¹⁸ operated by signal W¹⁸ and wires 38 and 34 back to contact member 16 of circuit controller K¹⁸. When this circuit is closed 115 section A-B is supplied with alternating track circuit current of normal relative polarity by transformer T⁸.

Signal W¹⁵ controls transformers T⁴ and T⁶ in the same manner as just described in 120 connection with the control of transformers T⁴ and T⁶ by signal W¹⁸ and in addition signal W¹⁵ controls transformer T⁸ as follows: Contact members 15 and 24 of circuit controller K¹⁵ are connected by means of 125

- wires 40 and 41 with the terminals of secondary 13 of transformer O^H and the circuit for transformer T^s passes from contact member 23 of circuit controller K^{15} , through 5 wire 39, front contact 42 of relay R^4 , wire 43, front contact 46 of track relay R^{11} , wire 47, circuit controller P^s operated by signal W^s , wire 48, primary 12 of transformer T^s , and wires 20 and 49 back to contact members 10 16 and 29 of circuit controller K^{15} . This circuit is closed only when relays R^4 and R^{11} are both energized and signal W^s is indicating stop, under which conditions section E—F is supplied with alternating track circuit current of normal relative polarity when signal W^{15} indicates caution or proceed or with alternating track circuit current of reverse relative polarity when signal W^{15} indicates stop.
- 15 20 The control of transformers T^s , T^7 and T^9 by signals W^{14} and W^9 will be readily understood from the foregoing. Signals W' and W^4 control certain apparatus part of which is associated with portions of track not shown in the drawing in a manner which will be apparent from the drawing and will be understood without further description.
- 25 Means are also provided for supplying to the rails in parallel of each track section a current which I will hereinafter term a "local" current. For this purpose I connect an impedance 4 across the rails adjacent the left hand end of each section and a similar impedance 4^a across the rails adjacent the 30 right hand end of each section. The connections for the local circuits are then made to the mid-point of these impedances. The immediate supply of local current for each track section is a local transformer designated by the reference character U with an appropriate exponent and having its primary winding constantly energized from one winding of the two-phase alternator M over line wires 3 and 3^a . Referring for example 35 to section A—B, the local circuit for this section passes from secondary 52 of transformer U^A , through wire 53, impedance 4^a in section A—B, through the rails of the section to impedance 4, and wire 54, back to secondary 52 of transformer U^A . It is therefore clear that section A—B is constantly supplied with local current. Similar local circuits are provided for each of the remaining sections except for section H—J and the 40 partial section immediately to the left of point A. The local circuit for section H—J is the same as just explained for section A—B except that a contact 8 controlled by switch 7 of passing siding X^2 is inserted in this circuit. The contact 8 is so arranged that it is closed when switch 7 is in such a position as to allow movements of traffic through the section H—J, but is open when switch 7 is in such a position as to allow 45 movements of traffic, into or out of passing siding X^2 . It follows that local current is supplied to section H—J only when switch 7 is in such position as to permit traffic movements through this section. Contact 8 of switch 7 of passing siding X' controls the local circuit of the section immediately to the left of point A in a similar manner.
- 50 Before explaining the operation of the apparatus as a whole, it should be pointed out that the trackway apparatus here shown and described is suitable for, though by no means limited to, co-operation with train carried governing means in the following manner: When the train occupies a stretch of track which is supplied with track circuit current of normal relative polarity and also with local current a proceed indication is received on the train. When the portion of track occupied by the train is supplied with track circuit current and local current the relative polarity of either of which currents is reversed, the train receives a caution indication and when the train is on a stretch of track to which the supply of track circuit current or local current is for any reason interrupted, a stop indication is received on board the train.
- 55 The indications are received on board the train in at least one form of train carried apparatus arranged to function in this manner through the medium of certain pick-up apparatus located on the train in advance of the forward axle. In apparatus of this type it is evident that the source of track circuit current must always be located in advance of the train as otherwise the track circuit current would be shunted away from the pick-up apparatus by the wheels and axles of a train. In my present invention it will be clear that for traffic movements in either 60 direction through the stretch of track shown in the drawing, the supply of track circuit current is always located at the end of the section towards which the train is proceeding.
- 65 In such systems it is desirable to have the track circuit current displaced in phase with respect to the local currents. In my invention this is accomplished by supplying the local transformer with current from one winding of generator M and supplying the track transformer from the other phase of this generator. The local currents and track circuit currents are therefore in quadrature.
- 70 As shown in the drawing, all of the apparatus is in the condition corresponding to an unoccupied condition of the track, that is, all of the signals W are indicating proceed, all of the track relays R are energized by their associated batteries 10, and all of the stick relays S are de-energized. Switches 7 associated with passing sidings X' and X^2 are each in such position as to permit movement of traffic through the stretch of single track. In explaining the 75

operation of the apparatus, I will first assume that a westbound train moves through the stretch of track shown in the drawing. As this train passes signal W^4 , this signal moves to stop position and the opposing signals W' , W^5 , W^6 and W^{15} also move to stop position. Signal W^8 however, indicates proceed, and as a result track circuit current of normal relative polarity is supplied to section G—H by track transformer T^{13} . Local current is also supplied to this section by secondary 51 of transformer U^6 , and the train therefore receives a proceed indication as it passes through this section. As the train enters section F—G, relay R^{11} becomes de-energized thus interrupting the supply of alternating track circuit current to section G—H and completing the circuit at back contact 54 of relay R^{11} for transformer T^{11} which now supplies alternating track circuit current of normal relative polarity to section F—G; at the same time local current is supplied to this section through secondary 52 of transformer U^6 . The train therefore still receives a proceed indication. The entrance of the train into section E—F causes the energization of relay S^8 and causes signal W^8 to indicate stop. Signal W^{14} is, however, at proceed and therefore track circuit current of normal relative polarity is supplied to section E—F by transformer T^9 and local current is supplied to this section by secondary 52 of transformer U^6 . The train therefore receives a proceed indication throughout section E—F. It will be obvious from the drawing that as the train proceeds successively through sections D—E, C—D, B—C, A—B, etc., the proceed indication will continue to be received on board the train. I will assume however that after moving into section E—F, the train stops. Under these conditions relay R^{11} is again energized by current from battery 10 and track circuit current of reverse relative polarity is therefore supplied to section G—H from front contact 18 of stick relay S^8 , but no alternating track circuit current is supplied to section F—G since circuit controller K^8 is reversed, signal W^8 indicating stop. If, now, a following train enters the stretch of track shown in the drawing it will receive a caution indication throughout section G—H and will receive a stop indication due to the interruption of alternating track circuit current as the train proceeds through section F—G. If the train attempts to enter section E—F it will continue to receive a stop indication since the alternating track circuit current supplied to this section by transformer T^9 is shunted away from the pick-up apparatus of the following train by the wheels and axles of the train already occupying section E—F. Similar protection is afforded against following trains throughout the stretch. The operation of the ap-

paratus when the stretch is traversed by eastbound traffic is similar to that for westbound traffic and will be understood without further explanation.

I will now assume that an eastbound train enters the stretch of track and stops in section A—B. Signals W^{18} , W^{14} , W^8 and W^4 will then, of course, display stop indications. If, under these conditions, a train moving from right to left attempts to pass through the stretch of track it will receive a stop indication throughout this stretch. When the train is in section G—H it will not receive track circuit current as the supply of current to transformer T^{13} is interrupted at front contact 18 of stick relay S^8 since circuit controller K^8 is now reversed, because signal W^8 indicates stop. As the train enters section F—G it will continue to receive a stop indication since relay R^{11} then becomes de-energized and the supply of current to primary 12 of transformer T^{11} is then interrupted. In a similar manner the supply of track circuit current to each section is interrupted for moves from right to left.

If a train moving from right to left passes signal W^4 , trains moving from left to right and subsequently entering the stretch will receive a stop indication in a similar manner.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track divided into a forward section and a rear section, a signal controlled by traffic conditions in advance of said forward section, a relay arranged to be energized when a train passes said signal moving in the direction in which the signal governs, and means controlled by said relay and by said signal for supplying track circuit current to the rails of said sections.

2. Railway traffic controlling apparatus comprising a stretch of railway track divided into a forward section and a rear section, a signal controlled by traffic conditions in advance of said forward section, a stick relay associated with said signal, and means controlled by said stick relay and by said signal for supplying track circuit current to said rear section and said forward section.

3. Railway traffic controlling apparatus comprising a stretch of railway track divided into a forward section and a rear section, a signal controlled by traffic conditions

- in advance of said forward section, a stick relay associated with said signal, means controlled by said signal for supplying track circuit current to said forward section, and 5 means controlled by said signal and by said stick relay for supplying track circuit current to said rear section.
4. Railway traffic controlling apparatus comprising a stretch of railway track divided into a forward section and a rear section, a signal controlled by traffic conditions in advance of said forward section, and means controlled by said signal and responsive to traffic conditions in said forward section 10 for supplying track circuit current to said sections.
5. Railway traffic controlling apparatus comprising a stretch of railway track divided into a forward section and a rear section, means controlled by traffic conditions in advance of said forward section, a source 20 of energy constantly connected with said forward section, a track relay also constantly connected with said forward section and responsive to energy from said source, and means controlled by said relay and by said means for supplying alternating track circuit current to said sections.
6. Railway traffic controlling apparatus comprising a stretch of railway track divided into a forward section and a rear section, a signal controlled by traffic conditions in advance of said forward section, a source 30 of energy constantly connected with said forward section, a track relay also constantly connected with said forward section and responsive to energy from said source, means for supplying said rear section with track circuit current of one relative polarity when 35 said signal indicates proceed or caution and of the other relative polarity when the signal indicates stop, provided said relay is energized.
7. Railway traffic controlling apparatus comprising a stretch of railway track divided into a forward section and a rear section, a signal controlled by traffic conditions in advance of said forward section, a source 45 of energy constantly connected with said forward section, a track relay also constantly connected with said forward section and responsive to energy from said source, and means controlled by said relay for supplying said rear section with track circuit current 50 of one relative polarity when the signal displays a more restrictive indication and of the other relative polarity when the signal displays a less restrictive indication.
8. Railway traffic controlling apparatus comprising a stretch of railway track divided into a forward section and a rear section, means controlled by traffic conditions in advance of said forward section, a source 60 of energy constantly connected with said forward section, a track relay also constantly connected with said forward section and responsive to energy from said source, a first track transformer having its secondary 65 constantly connected with the rails of said rear section, a second transformer having its secondary constantly connected with the rails of said forward section, a stick relay associated with said signal, a circuit includ-
- stantly connected with said forward section and responsive to energy from said source, and means controlled by said relay for supplying said rear section with track circuit current of one relative polarity when traffic 70 conditions in advance of said forward section are safe, and of the other relative polarity when traffic conditions in advance of said forward section are dangerous, and means controlled by said relay and by said first 75 means for supplying track circuit current to said forward section.
9. Railway traffic controlling apparatus comprising a stretch of railway track divided into a forward section and a rear section, a signal controlled by traffic conditions in advance of said forward section, a source 80 of energy constantly connected with said forward section, a track relay also constantly connected with said forward section and responsive to energy from said source, and means controlled by said relay for supplying said rear section with track circuit current of one relative polarity when the signal displays a more restrictive indication 85 and of the other relative polarity when the signal displays a less restrictive indication, and means controlled by said relay for supplying track circuit current to said forward section when the signal displays a less restrictive indication.
10. Railway traffic controlling apparatus comprising a stretch of railway track divided into a forward section and a rear section, a signal controlled by traffic conditions 100 in advance of said forward section, a source of energy constantly connected with said forward section, a track relay also constantly connected with said forward section and responsive to energy from said source, means 105 for supplying said rear section with track circuit current of one relative polarity when said signal indicates proceed or caution and of the other relative polarity when the signal indicates stop provided said relay is energized, and means for supplying said forward section with track circuit current when said relay is de-energized and said signal displays a proceed or a caution indication.
11. Railway traffic controlling apparatus comprising a stretch of railway track divided into a forward section and a rear section, a signal controlled by traffic conditions in advance of said forward section, a source 110 of energy constantly connected with said forward section, a track relay also constantly connected with said forward section and responsive to energy from said source, a first track transformer having its secondary 115 constantly connected with the rails of said rear section, a second transformer having its secondary constantly connected with the rails of said forward section, a stick relay associated with said signal, a circuit includ-

ing a front contact of said track relay, a back contact of said stick relay, and a contact controlled by said signal for supplying the primary of said first transformer with 5 current of one relative polarity, a circuit including a front contact of said stick relay and a contact controlled by said signal for supplying current of the other relative polarity to the primary of said first transformer, and a circuit for the primary of 10 said second transformer including a back contact of said track relay and a contact controlled by said signal.

12. Railway traffic controlling apparatus 15 comprising a stretch of railway track divided into a forward section and a rear section, a signal controlled by traffic conditions in advance of said forward section, and means controlled by said signal for supplying track circuit current to said rear and 20 said forward sections, and means for constantly supplying local current to said sections.

13. Railway traffic controlling apparatus 25 comprising a stretch of railway track divided into a forward section and a rear section, a signal controlled by traffic conditions in advance of said forward section, and means controlled by said signal for supplying track circuit current to said rear and 30 said forward sections; a direct current track circuit for each section including a source of direct current, a track relay, and the rails of the section; means for constantly supplying each section with local current, means 35 for supplying said rear section with track circuit current of one relative polarity or the other according to the indication displayed by said signal, and means for supplying said forward section with track circuit current or not according to the indication 40 displayed by said signal.

14. Railway traffic controlling apparatus 45 comprising a stretch of railway track divided into a forward section and a rear section, a signal controlled by traffic conditions in advance of said forward section, and means controlled by said signal for supplying track circuit current to said rear and 50 said forward sections, a direct current track circuit for each section including a source of direct current, a track relay, and the rails of the section, means for constantly supplying each section with local current, means 55 controlled by the track circuit for said forward section for supplying said rear section with alternating track circuit current of one relative polarity or the other according to the indication displayed by said signal, and means also controlled by said track circuit 60 for the forward section and by said signal for supplying said forward section with alternating track circuit current.

15. Railway traffic controlling apparatus 65 comprising a stretch of railway track di-

vided into a forward section and a rear section, a signal controlled by traffic conditions in advance of said forward section, a stick relay associated with said signal, means for supplying alternating track circuit current 70 to said rear section, and means for interrupting such supply when said signal indicates stop unless said stick relay is energized.

16. Railway traffic controlling apparatus comprising a stretch of railway track 75 divided into a forward section and a rear section, a signal controlled by traffic conditions in advance of said forward section, a relay arranged to be energized when a train passes said signal moving in the direction 80 in which the signal governs, means for supplying said rear section with alternating current of one relative polarity or the other according to the indication displayed by the signal and effective to interrupt such supply 85 when said signal indicates stop unless said relay is energized.

17. Railway traffic controlling apparatus comprising a stretch of railway divided into 90 a first section, a second section, and a third section, a signal for governing traffic moving in one direction away from said first section, a second signal for governing traffic entering said third section in the other direction, means controlled by said first and 95 said second signals for at times supplying alternating track circuit current to said third section and governing means controlled by said current.

18. Railway traffic controlling apparatus 100 comprising a stretch of railway divided into a first section, a second section, and a third section, a signal for governing traffic moving in one direction away from said first section, a normally de-energized relay arranged to be energized when a train passes 105 said signal moving in the direction in which said signal governs, a second signal for governing traffic entering said third section moving in the opposite direction, means controlled by both said signals and by said relay for supplying track circuit current to 110 said third section, and governing means responsive to said current.

19. Railway traffic controlling apparatus 115 comprising a stretch of railway divided into a first section, a second section, and a third section, a signal for governing traffic moving in one direction away from said first section, a normally de-energized relay arranged to be energized when a train passes 120 said signal moving in the direction in which said signal governs, a second signal for governing traffic entering said third section moving in the opposite direction; a track circuit for said second section including a source of energy, the rails of the section and a track relay; means controlled by said two signals, said first relay and said track relay 125 for supplying alternating current to said 130

third section, and governing means responsive to said current.

20. In combination, a stretch of railway track divided into a forward section and a rear section, a pole changer capable of assuming two positions and arranged to assume one position or the other in accordance with traffic conditions in advance of said forward section, a track relay for said forward section, means including a front contact of said relay and said pole changer for supplying alternating track circuit current to said rear section, and means including a back contact of said relay and said pole changer for supplying alternating track circuit current to said forward section. 55
21. In combination, a stretch of railway track divided into a forward section and a rear section, a pole changer capable of assuming two positions and arranged to assume one position or the other in accordance with traffic conditions in advance of said forward section, a track relay for said forward section, a stick relay arranged to be energized when a train moving away from said rear section leaves said forward section, and means controlled by said stick relay and including a front contact of said track relay for at times supplying said rear section with alternating track circuit current, and means controlled by said pole changer but not by said stick relay and including a back contact of said track relay for supplying said forward section with alternating track circuit current. 60
22. In combination, a stretch of railway track divided into a forward section and a rear section, a pole changer capable of assuming two positions and arranged to assume one position or the other in accordance with traffic conditions in advance of said forward section, a track relay for said forward section, a stick relay arranged to be energized when a train moving away from said rear section leaves said forward section, means controlled by said stick relay 65
25. In combination, a two phase alternator having two windings in which the currents are in quadrature, a stretch of railway track, means for supplying alternating current to the rails of said stretch in series from one said winding, and means for supplying alternating current to the rails of said stretch in parallel from the remaining winding. 70
26. In a railway traffic controlling system, comprising a stretch of railway track divided into successive sections, a track circuit for each section including the track rails in series, and a local circuit for each section including the track rails in multiple, the combination with the above-mentioned instrumentalities of a two phase quadrature alternator having two windings and means for supplying current to all said local circuits from one said winding and to all said track circuits from the remaining said winding. 75
27. In testimony whereof I affix my signature. 80
RONALD A. McCANN. 90
